CLAIM

We claim the ornamental design for an electronic data device, substantially as shown and described.

DESCRIPTION

FIG. 1 is a front view of an electronic data device embodying the design of the present invention;

FIG. 2 is a rear view, thereof;

FIG. 3 is a left side view, thereof;

FIG. 4 is a right side view, thereof;

FIG. 5 is a top view, thereof; and,

FIG. 6 is a bottom view, thereof.
